UNITED STATES PATENT OFFICE.

HARRY E. BOYRIE, OF SAN FRANCISCO, CALIFORNIA, ASSIGNEE TO ANDREWS-BRADSHAW COMPANY, OF PITTSBURGH, PENNSYLVANIA, A CORPORATION OF PENNSYLVANIA.

FLUID SEPARATOR.

Application filed January 28, 1926. Serial No. 84,321.

This invention relates to steam separators and particularly to such separators to be used with locomotives and the like. In my co-pending application for patent, Serial No. 5 39,201, filed June 24, 1925, I have illustrated and described a fluid separator which comprises a combination of baffle means for breaking up the bubbles in the steam and centrifugal separating means for separating 10 the moisture from the steam. This present invention is an improvement on that invention and particularly in applying that invention to locomotives. The details of 15 the invention as set forth in said application are not particularly essential to the present invention and hence are not fully set forth herein; but reference may be had to that application for such details.

Of the accompanying drawings Fig. 1 is 20 a side elevation of a steam separating system which embodies the features of my invention, a portion of the system being shown in section; Fig. 2 is a front elevation of the same; Fig. 3 is a reduced plan view of a portion of 25 the system; and Fig. 4 is an enlarged plan view of one of the separating units with a portion thereof broken away to show the baffles.

I have found it desirable, in many cases in 30 separating the moisture from the steam, or in purifying steam, to pass the steam first through a series of baffles, against which the particles of moisture in the steam are thrown, so as to break up the bubbles, particularly, when there is more or less foaming 35 in the boiler. This not only disrupts the moisture particles, but it separates much of the moisture from the steam. In carrying out my invention, I then pass the steam 40 through a centrifugal separator which is arranged to throw the remaining particles of moisture and other impurities outwardly away from the steam and thus to allow the dried steam to pass into the steam system 45 without carrying with it any moisture or other impurities.

The means which I prefer for carrying out this method of operation in this instance comprises a bank or banks of baffles 10, 50 which are adapted to break up the bubbles or drops of water. This bank is itself a steam separator and for convenience in this instance may be called the first separator.

From these baffles the steam passes through 55 an outlet 11, which is an opening in a horizontal plate 12 mounted in the steam dome of the boiler. The plate 12 entirely separates the upper portion of the dome from the lower portion except for the outlet 11. The steam pipe 14, together with the valve operating rod 15, pass through the plate. This rod 15 is arranged to operate the throttle valve 16 to allow the steam to pass in the usual manner from the upper end of the dome out into the steam system of the 60 locomotive.

After the steam enters the upper chamber 17 of the dome it passes through throttle valve 16 and the pipe 14 into and through the centrifugal separator 26. From this 70 separator the steam and moisture pass into the casing 18 which has a chamber 19. The casing may be designated as the water collector. In this chamber 19 a steam outlet 20 projects and from this outlet the steam 75 passes to the steam main 21 of the system. In the lower portion of the collector the water from the centrifugal separator collects, as it is separated from the steam; and, connected to this chamber is a drain pipe 22. 80 The separated water passing into the drain pipe is carried out wherever desired through the pipe 23. And a vent pipe 24 connects the drain pipe with the chamber 19 and prevents clogging up of the drain pipe by 85 relieving the back pressure and allowing any air or steam which may be entrained in the water to pass back to the water collector.

Any suitable type of baffles may be used in the first separator for breaking up the bubbles. I prefer for the purpose the trough shaped baffles 25 which are mounted vertically and through which the steam passes on its way from the boiler to the outlet 11. By reducing the space between the baffles 90 sufficiently the steam passes through these baffles at a very high velocity and the bubbles are thus broken and crushed against the sides so that the steam passing out of the outlet 11 is substantially free from 100 bubbles, and the drops of water are materially broken up. A large portion of the moisture from these bubbles is separated from the steam while it is passing through these baffles and flows back into the boiler. 105 The banks of baffles may be fixed to the plate

12, and may be removed with the plate for cleaning or other purposes.

Any suitable type of centrifugal separator may be used for completely separating the moisture from the steam after it has passed through the separator 10 and the throttle valve. I prefer for the purpose the centrifugal separator 26, which has spiral-shaped conduits 27 so arranged that the steam and moisture as they pass through are given a rotary forward movement; and as they pass out of the outlet 28 the moisture, and other impurities, being denser than the steam, are thrown outwardly along the inner surfaces 15 of the water collector and pass down into the chamber 19 and out through the drain pipe 22, while the steam is forced out of the collector through the central outlet 20.

It will be understood that additional separators may be used either in parallel with these or in series therewith, so as to increase the effectiveness of the separation, or so as to provide greater capacity of the separating system. Or other changes might be made 25 in the arrangement of the various parts or the details thereof by those skilled in the art without departing from the spirit of my invention as disclosed by the claims herein.

30 I claim as my invention:

1. In a boiler system, the combination of a dome, a horizontal plate mounted in said

dome, said plate having an opening therethrough, a foam breaker mounted beneath said plate, said breaker having a steam inlet 35 and a steam outlet, said outlet registering with said opening, a throttle valve mounted above said plate, means for opening and closing said valve, a steam separator mounted in said boiler, a pipe connecting said 40 valve with said separator, and a pipe connected to said separator and passing out of said boiler.

2. In a boiler having a dome, a horizontal plate mounted in the central portion of 45 said dome and having an opening therethrough, a foam breaker suspended from said plate, said breaker having a steam inlet and a steam outlet, the outlet of said breaker registering with said opening, said dome 50 having a detachable cover thereon, a throttle valve mounted in said dome above said plate, means for opening and closing said valve, said valve having a steam inlet and a steam outlet, a steam separator mounted in said 55 boiler and having a steam inlet and a steam outlet, communicating means connecting said valve outlet with said separator inlet, and a pipe connected to said separator outlet and passing out of said boiler.

60 In testimony whereof, I hereunto set my hand.

HARRY E. BOYRIE.
